UNITED STATES PATENT OFFICE

HARRY E. LA BOUR, OF HOMEWOOD, ILLINOIS

SEWAGE EJECTOR

Application filed January 20, 1927. Serial No. 162,295.

This invention relates to means for handling sewage, and the like, such as is required for raising sewage from a lower level to a higher level.

5 Sewage ejectors of the pneumatic type are in common use. They require compressed air which is often difficult and expensive to provide. The operation is expensive because of the loss of energy in the compressed 10 air. The pneumatic ejector depends for its successful operation upon keeping the inlet check valve tight. In case this valve does not close the pressure exerted by the compressed 15 air discharges the accumulated sewage back into the line and failure of the system results.

Because of the simplicity of the centrifugal pump, various attempts have been made to utilize the same directly for this work and, in fact, there are a number of pumps on the 20 market, but a centrifugal pump which is designed for anything like efficient operation cannot be built to take care of solid matter except in a finely divided form. For this reason the centrifugal pump has been 25 only partially successful.

Heretofore the pump has been disposed in a pit at or below the sump with the result that it is in an undesirable position, particularly for direct drive by a motor.

30 In the preferred embodiment of the present invention, I provide a sump and between the incoming sewer and the sump I provide a strainer to intercept such solids as cannot be efficiently handled by the pump. As a

35 novel feature of my invention I employ a self priming pump operated directly by a motor, this pump being preferably of the type disclosed in my prior Patent No. 1,578,236, which pump is disposed in a convenient position above the sump. This pump

40 takes the effluent from the sump and discharges the same back through the strainer to drive the solid material thereupon into the discharge to the sewer main. I provide a

45 lateral outlet from the incoming sewer pipe or service pipe to relieve any leakage of the inlet check valve when the pump is in operation, so that in no case can the pump discharge the sewage back into the service mains.

I interpose a screen in this lateral outlet so that solid matter will not be discharged into the sump, but will be retained in the inlet connection until such time as the inlet check valve is again opened. The strainer 55 is disposed in a tank which is in turn disposed within the sump, said sump being preferably a concrete basin. Obviously, this may be varied within my invention. As a further feature of my invention I provide means for 60 positively closing the outlet of the effluent discharge from the strainer so that the full force of the pump may be exerted upon the discharge of the effluent and dislodgment of the solid matter from the strainer. It is an 65 important feature of this invention that the same can be applied to pits or sums now in existence. The pump and motor being disposed above the pit permit of a mode of operation and a capacity which other methods 70 of operation do not permit.

While I explain the invention with reference to the handling of sewage and with reference to the details of a specific embodiment, it is to be understood that the invention is not to be limited to the particular 75 use nor to the details of construction.

In order to acquaint those skilled in the art with the manner of constructing and operating a device embodying my invention, 80 I shall now describe in connection with the accompanying drawings a specific embodiment of the same.

In the drawings:—

Figure 1 is a vertical section through the 85 sump showing the strainer box and pump in elevation, part of the strainer box being broken away to show the valve construction;

Figure 2 is a vertical section taken at right angles to the view of Figure 1 through the 90 strainer box and connections thereto; and

Figure 3 is a fragmentary elevational view showing a modified form of outlet valve.

A suitable sump is provided preferably in the form of a concrete pit 1, and this pit is 95 provided with a cover member 2. Within the pit there is disposed the strainer box 3. Obviously the strainer box may be disposed in a separate pit from the one forming the sump, but it is a desirable feature of the in- 100

vention to have the strainer box 3 disposed within the sump. This strainer box 3 is supported on a suitable bracket 4 mounted on the side wall of the pit 1. The strainer box contains a strainer plate 5 which may be of perforated sheet metal, or the like, and in the present instance is a flat plate disposed diagonally within the confines of the box 3, which box may be rectangular or circular in form, or any desired form. The strainer box 3 may be made of a casting having suitable inlet and outlet connections as will be explained later. A cover member 6 is secured to the top of the box 3, being fastened by suitable flanges or the like. The strainer 5 divides the box 3 into two compartments 7 and 8, the compartment 7 being on the incoming side of the sewage and being arranged to intercept solid matter such as cannot conveniently be handled by a centrifugal pump. The incoming service main 9 opens into the chamber or compartment 7 and it has a check valve 10 which, in the present instance, is located just inside the compartment 7, although obviously this might be located in the main 9 if desired.

I provide an overflow connection which in the present instance consists of an open stand-pipe 11 extending up to substantially the top 30 of the sump, and in this open connection I provide a screen or strainer 12. The check valve should be located between said overflow connection 11 and the chamber 7, so that as will be described later, when the pressure 35 of the pump is applied to discharging the solid and liquid matter from said chamber 7, the check valve 10 will close and prevent the discharge of sewage from the chamber 7 back into the service main 9.

40 Preferably a slight enlargement or chamber 13 is formed below the strainer 12 so that solid matter may be retained therein during the time that the check valve is closed or partly closed.

45 A sewage discharge connection comprising a pipe 14 is connected to the interior of the chamber 7 preferably at the lower end of the screen or strainer 5. A non-return valve 15 is preferably interposed in said discharge line 14. This discharge line 14 runs to the sewer main for the discharge of the sewage from this part of the system.

The chamber or compartment 8 has two connections; one, an outlet connection 17 for 55 the outlet of effluent, that is, the liquid which remains after the solid matter has been intercepted, and the effluent flows through the connection 17 into the sump providing a body of liquid 18 which may be satisfactorily handled by the pump 19.

This connection 17 is preferably placed adjacent the top of the box 3 for the purpose of retaining the box substantially full of liquid, so that any solid matter remaining on 60 the screen will be wet with liquid, first to

prevent it from drying upon the screen or strainer and, second, so that its weight is borne in part by the liquid according to the law of Archimedes.

The pump 19 has a suction pipe 20 leading 70 to the lower part of the sump and it has a discharge connection comprising a pipe 21 leading into the chamber 8 preferably near the bottom of the same.

Since, as will be apparent from the description of operation later, it is necessary to close the outlet 17 when the pump 19 is discharging liquid from the sump into the chamber 8, I provide a valve which is closed when the pump 19 operates. The valve may be provided to close in a number of different ways. I have shown the preferred manner which consists in causing the liquid flow of discharge from the pump 19 creating a positive force for closing the valve 22. This valve 22 is a lift valve 80 closing the opening of the discharge connection 17 and seating with internal pressure in the chamber 8.

The valve is mounted on a swinging lever 23 pivoted at 24 within the chamber 8. 90

The lever 23 has a continuation 25 upon which is mounted a vane or piston 26 fitting loosely in a cylinder or pocket 27 connected to the discharge pipe 21.

95 The pump 19 is preferably of the type disclosed in my patent above mentioned and it comprises a pump casing 28 in which there is mounted a suitable runner, the shaft 29 of which is directly connected to an electric motor 30 for driving the same. The pump has a separating chamber 31 in which gas and liquid are separated, the air being discharged out of the discharge pipe 21 and the liquid being in part during the priming operation returned to the pump casing and into the runner to perform the priming operation, as is described in the aforesaid patent.

100 The motor 30 is controlled by the float controlled switch 32, a suitable operating float 33 being disposed within the sump and subject to the level of the liquid 18. Provision is made for starting the pump when a predetermined high level is attained and for stopping the pump when a predetermined low level is attained, as is well understood by those skilled 105 in the art.

110 I provide a flushing connection 34 which comprises a pipe leading to a source of water under pressure and having branches 35 and 36 leading to suitable flushing nozzles 37 and 38, respectively. A suitable control valve 39 is provided. Separate valves may be provided in the branches 35 and 36, if desired. The purpose of these flushing nozzles is to provide means for periodic cleaning of the screens or 115 strainers 5 and 12, respectively.

120 In Figure 3 I have shown a modified form of valve for closing the outlet 17, this valve comprising a hinged flap valve 40 adapted to be held normally by gravity in a vertical posi- 130

tion. An extension 41 of the discharge pipe 21 is placed in such position that the liquid discharged by the pump strikes the valve 20 and swings it against the seat 42 which is arranged at an angle to the vertical, so that it normally is open when no liquid is flowing out of the discharge pipe 41, but so that the discharge of liquid from the pipe 41 will press the valve 40 to its seat 42 and close off the connection 17.

The operation of the system is as follows.

Liquid enters the compartment 7 through the incoming service main 9, the valve 10 being automatically swung open and permitting the raw sewage to be discharged into the compartment 7. Solid matter is intercepted by the screen or strainer 5 and the effluent or liquid portion passes into the compartment 8, filling the same to the level of the discharge connection 17 and then flowing out the discharge connection 17 into the sump formed in the basin 1.

The solid matter such as cannot be handled by the pump 19 is retained in the chamber 7, and the proportions of the system are so determined that the level of the liquid 18 will rise and start the pump before an excessive accumulation of solid matter in the chamber 7 occurs.

At this time the valve 22 is opened, being swung open by gravity.

The piston or disc 26 does not necessarily close off the discharge connection of the pump 19 as there is no necessity for so doing, the pipe 21 extending above the top of the sump and above the top of the box 3.

When the liquid 18 has risen to the point where the switch 32 is closed, to energize the circuit of the motor 30 the pump is started and it quickly picks up its own suction, raising liquid from the sump and discharging the same through the discharge connection 21. The discharge of liquid pushes the piston or disc 26 outwardly, in a clockwise direction as viewed in Figure 1, swinging the arms 25 and 23 about the pivot 24 and closing the valve 22.

Thereupon pressure builds up in the compartment 8 and liquid with the contained solid matter is then driven out through the discharge connection 14 past the check valve 15.

The check valve 10 in the incoming line 9 is automatically closed. In the event that this valve should leak or should be blocked partly open, the leakage therefrom merely backs up in the service main 9 to the point of the level of the stand-pipe 11, the liquid thereupon overflowing into the sump in the pit 1 doing no further harm than lowering to some extent the efficiency of the pump. It is to be observed that of the incoming raw sewage, or of the sewage discharged from the compartment or chamber 7, solid matter

is prevented from entering the sump by the intercepting screen or strainer 12.

Likewise, during the operation of discharge by the pump any raw sewage tending to accumulate will deposit its solid matter in the chamber 13 and the liquid effluent will overflow the stand-pipe 11 and be discharged into the sump.

Obviously the service main 9 may enter the chamber 7 at any convenient point, that is, it is not restricted to entering the chamber 7 at the upper portion thereof.

An attendant periodically inspects the plant and flushes the screens or strainers 5 and 12 with water under pressure through the nozzles 38 and 37, respectively.

Upon lowering of the level in the sump to a predetermined minimum, the switch 32 opens the motor circuit and the pump stops. Thereupon the liquid in the chamber 8 tends to siphon back through the pipes 21, pump 19, pipe 20, into the sump and this action, together with gravity acting on the levers 23 and 25, positively opens valve 22.

At the same time the siphoning action puts a suction on the inner end of the connection 17 tending to open the valve 22.

The valve arrangement shown in Figure 3 may be employed. It need not be placed in the lower part of the compartment 8. If desired, an additional weighted arm may be connected to the valve 40 to assist its opening operation.

I do not intend to be limited to the details shown and described.

I claim:—

1. In combination, a strainer, a first chamber on one side of the strainer, a second chamber on the other side of the strainer, an inlet, and a discharge for the first chamber, an outlet for effluent and a pump discharge connection for the second chamber, said outlet being above said discharge connection to maintain said chambers partially filled with effluent at all times, means for receiving the effluent from said outlet, and a self priming centrifugal pump disposed above the level of said inlet for pumping liquid from said receiving means and discharging the same into the second chamber through said pump discharge connection to drive the effluent and solid matter out through the discharge, said pump and its connections siphoning a part of the effluent from said chambers to clean the pump, said siphon being broken by air drawn into the outlet of said second chamber to form a trap in the pump to prevent the further flow of effluent through it.

2. In combination, a strainer, a first chamber on one side of the strainer, a second chamber on the other side of the strainer, an inlet and a discharge for the first chamber, an outlet for effluent and a separate pump discharge connection opening into the second chamber below the effluent outlet, means

- for receiving the effluent from said outlet, a pump for driving the effluent from said receiving means to said pump discharge connection, said pump having an inlet connection in the receiving means below said discharge connection and a valve in the strainer chamber to close said outlet for effluent, said valve being closed by pressure in said pump discharge connection when said pump is operated, and opened by siphoning as the effluent in said second chamber flushes back through the pump when it is shut down. 5
3. In combination, a sump, a strainer box therein comprising a strainer, a first chamber on one side of the same, and a second chamber on the other side of the same, an inlet and a discharge for the first chamber, a check valve for said inlet, an outlet for effluent for the second chamber, a pump having an inlet connection with the sump, a pump discharge connection for the second chamber, said sump receiving the effluent from said outlet, a valve for closing said outlet when the pump is operated, and an open by-pass connection leading from said inlet to 10 said sump. 15
4. In combination, a pump, a strainer, a first chamber on one side of the same, a second chamber on the other side of the same, an inlet and a discharge for the first chamber, a check valve for said inlet, an outlet for effluent for the second chamber, a pump discharge connection for the second chamber, a sump for receiving the effluent from said outlet, a valve for closing said outlet when the pump is operated, and an open by-pass connection leading from said inlet to said sump, said by-pass comprising a stand-pipe, and a screen in said by-pass for intercepting 20 solid matter. 25
5. In combination, a sump, a strainer box therein, a strainer dividing the box into a first compartment and a second compartment, an inlet connection for the first compartment, said connection comprising a check valve, a discharge connection communicating with the bottom of the first compartment, an outlet for effluent leading from the top of the second compartment to 30 the sump to prevent effluent from flowing through it into the sump unless said second compartment is filled, a self priming centrifugal pump mounted above the sump, and having a suction connection leading into the 35 sump and a discharge connection leading into the second compartment, said pump and its connections forming a siphon which withdraws a part of the effluent from said second chamber to clean the pump and connections and subsequently forming a trap to check further outward flow of effluent through the pump. 40
6. In combination, a sump, a strainer box, a strainer dividing the box into a first compartment and a second compartment, an inlet connection for the first compartment, said connection comprising a check valve, a discharge connection communicating with the bottom of the first compartment, an outlet for effluent leading from the top of the second compartment to the sump, a self priming centrifugal pump mounted above the sump and having a suction connection leading into the sump and a discharge connection leading into the second compartment, and a valve actuated upon the operation of the pump for closing off the said outlet, said pump and its connections forming a siphon which withdraws a part of the effluent from said second chamber to clean the pump and connections and subsequently forming a trap to check further outward flow of effluent through the pump. 45
7. In combination, a sump, a strainer box having a strainer dividing the same into two compartments, a separate inlet for the first compartment, an overflow connection for said inlet leading into the sump, a check valve for the inlet between the overflow connection and the box, a discharge connection communicating with the lower part of the first compartment, said sump receiving the effluent from the second compartment, and a pump for forcing the effluent from said sump back through the strainer. 50
8. In combination, a sump, a strainer box having a strainer dividing the same into two compartments, a separate inlet for the first compartment, an overflow connection for said inlet leading into the sump, a check valve for the inlet between the overflow connection and the box, a discharge connection communicating with the lower part of the first compartment, said sump receiving the effluent from the second compartment, a pump for forcing the effluent from said sump back through the strainer, and a screen for intercepting solid matter at said overflow connection. 55
9. In combination, a sump, a strainer box having a strainer dividing the same into two compartments, a separate inlet for the first compartment, an overflow connection for said inlet, leading into said sump, a check valve for the inlet between the overflow connection and the box, a discharge connection communicating with the lower part of the first compartment, means for receiving the effluent from the second compartment, a pump for forcing the effluent from said receiving means back through the strainer, a screen for intercepting solid matter at said overflow connection, and hydraulic flushing means for simultaneously flushing said strainer and said screen. 60
10. In combination, a sump, a strainer box having a strainer therein, a sewer inlet connection and a discharge connection communicating with the box on one side of the strainer, an outlet for effluent on the 65

other side of the strainer, a self priming pump above the sewer inlet connection, said pump having an inlet leading into the sump and a discharge connection leading into the strainer box on the said other side of the strainer, said pump and its connections forming a siphon which withdraws a part of the effluent from said second chamber to clean the pump and connections and subsequently forming a trap to check further outward flow of effluent through the pump.

11. In combination, a substantially cylindrical strainer box, a strainer therein comprising a substantially flat diagonal plate for intercepting solid matter dividing the box into a narrow bottomed chamber and a wide bottomed chamber, a discharge connection adjacent the lower end of the narrow bottom chamber, a sewage inlet connection for said strainer box on the same side of the screen as said discharge connection, a liquid inlet connection on the other side of the strainer, a liquid outlet connection on the same side as said liquid inlet, and a valve in the strainer box for said liquid outlet having means adapted to receive the impact of liquid from said liquid inlet connection.

12. In combination, a closed strainer box, a diagonal screen dividing the box into a first chamber and a second chamber, an inlet for raw sewage into the first compartment, a check valve on the inside of said compartment for said inlet, a discharge connection for the first compartment communicating with the lower portion of the same, a pump discharge connection connected to the lower part of the second compartment, and an effluent outlet for the second compartment, said outlet being provided with a valve in the strainer box adapted to be closed upon the inflow of liquid through the pump discharge connection.

13. In a system of the class described, a pit providing a sump, a strainer box in the pit above the sump, a screen defining two chambers in the strainer box, an inlet and a discharge connection for one chamber, a pump, the other chamber having connection with the sump directly and through said pump, said direct connection being located above the pump connection to maintain the chamber filled, said pump connection comprising a portion extending above the inlet connection and forming a trap to prevent flow from the inlet through the pump while it is idle.

14. In a system of the class described, a sump, a strainer box above the sump, a screen defining two chambers in the strainer box, an inlet and a discharge connection for one chamber, a pump, the other chamber having a drain connection with the sump and having a connection with the sump through said pump, said pump connection comprising a portion extending above the inlet connec-

tion to prevent back flow through the pump while it is idle, a valve for the drain connection, and control means for the valve operated by the direction of flow through said pump connection for closing the valve when the pump is in operation and drawing the valve open by siphonage upon stoppage of the pump.

15. In a system of the class described, a pit providing a sump, a strainer box in the pit above the sump, a screen defining two chambers in the strainer box, an inlet and a discharge connection for one chamber, a pump, the other chamber having a drain connection leading to the sump and having another connection leading to the sump through the pump, a valve in the strainer box for the drainage connection, and a piston member connected to the valve and operated by the liquid passing through said pump connection.

16. In a system of the class described, the combination of a well the bottom thereof forming a sump, a separating box for separating out solids disposed in said well, said box having an inlet and a discharge connection, said box having means for retaining solids adjacent said discharge connection, a drain connection for draining liquid from the box into the sump, a suction pump disposed above the sump, and adapted to draw liquid from the sump and flush the solids out of the box through the discharge connection and adapted to clean itself by siphonage at the completion of each of its operations.

17. In combination, a well, the bottom thereof forming a sump, a cover for the well, a strainer box supported in the well above the sump, a strainer dividing the box into two parts, an incoming sewer pipe passing through the wall of the well and entering one part of the box, a check valve in said part controlling said pipe, an effluent discharge pipe leading from the other part of the box, a sewage discharge pipe leading from the one part of the box, a self priming centrifugal pump mounted above the well and having an intake pipe leading down into the sump and a discharge pipe extending down into the well and connecting with the other part of the box, and an automatic valve in the box for closing the effluent discharge pipe when the pump is operated, said valve opening the effluent pipe responsive to back flow through the pump immediately after the pump is shut down.

18. In combination a strainer, a first chamber on one side thereof, a second chamber on the other side thereof, an inlet and a discharge for the first chamber, an outlet for effluent, a pump discharge connection for the second chamber, means for receiving the effluent from said outlet, and a self-priming centrifugal pump disposed above the level of the inlet, said pump having a suction pipe

extending down into said means and a discharge pipe extending to said pump discharge connection, said suction pipe, pump and discharge pipe forming a siphon extending above the level of the intake and while the pump is idle acting as a trap to prevent the outward flow of effluent from the second chamber.

19. In combination a strainer, a first chamber on one side thereof, a second chamber on the other side thereof, an inlet and a discharge for the first chamber, an outlet for effluent and a pump discharge connection for the second chamber, the pump discharge being disposed in the lower part of the second chamber, means for receiving the effluent from said outlet said means comprising a pit enclosing and extending below the strainer, and a self-priming centrifugal pump disposed above the level of the inlet, said pump having a suction pipe extending down into said pit and a discharge pipe extending to said pump discharge connection, said suction pipe, pump and discharge pipe forming an open connection providing an air trap extending above the level of the intake and preventing the outward flow of effluent from the second chamber while the pump is idle.

20. The method of cleaning the pump and connections employed to force effluent from a sump through an elevated screen box into a sewer which comprises, trapping a quantity of effluent in the screen box, siphoning a part of that effluent through the pump and connections to clean them, breaking the siphon with air drawn into the screen box by it, and trapping that air in the pump to prevent further flow of effluent from the box through the pump.

21. In combination, a pit, the bottom of which forms a sump, a box in the upper part of said pit, means for maintaining said box partially full of liquid, a pump located above said pit, piping connecting the discharge side of said pump to said box below the level of the liquid in it and connecting the suction side of the pump to said sump, said pump being operated to suck liquid from said sump and to force it into said box, means for discharging the liquid from the box, and means including said pump and piping for siphoning a part of the liquid in said box through the pump in a reverse direction to clean it when it has been shut down.

22. In combination, a pit the bottom of which forms a sump, a strainer box located in the upper part of said pit, a screen separating said box into a solids compartment and an effluent compartment, an inlet located near the top of said solids compartment and an outlet below said inlet, an outlet for said effluent compartment located near its top through which effluent flows into said sump after said box is filled above said solids compartment outlet, a pump located above said

pit, a suction pipe extending from the pump to a point in the pit below said box, a discharge pipe extending from the pump to said effluent compartment and entering it at a point below its outlet, said pump drawing effluent from said sump and forcing it and the solids in said solids compartment out through said solids outlet, said pump and piping permitting effluent in said box to siphon back through the pump immediately after it has been shut down to flush out sediment sucked into the pump from said sump, and a valve in said box for closing said effluent outlet when said pump is in operation and for opening it responsive to said siphonage.

23. In combination, a strainer box, a strainer therein separating the box into a first and a second chamber, said first chamber having an inlet located above its outlet, said second chamber having an outlet located below the inlet of the first chamber and above its outlet, an inlet for said second chamber located below its outlet and below the outlet of the first chamber, a pump located above said box, a sump located below the box, a pipe connection between the inlet of the second chamber and the discharge port of the pump, a suction pipe leading from said pump to said sump, means for admitting sewage to said first chamber in which chamber the solids are retained by said screen which permits the effluent to pass into the second chamber and through its outlet into said sump, said sump being operated to withdraw the effluent from the sump and to force it through the box to carry the solids in said first chamber through its outlet, a valve in the second chamber operated by pump pressure to close the outlet of said second chamber and operated by the siphoning of the effluent in said second chamber through the pump when it is shut down to open said outlet, said outlet when open admitting air to the box to break said siphon and thereby form a trap in said pump which prevents further flow of effluent through the pump to the sump.

In witness whereof, I hereunto subscribe my name this 17th day of January, 1927.

HARRY E. LA BOUR.
